DESIGN FOR A BULLDOZER

Harvey W. Rockwell, Cedar Rapids, Iowa, assignor to La Plant-Choate Manufacturing Co., Inc., Cedar Rapids, Iowa, a corporation of Delaware

Application March 12, 1945, Serial No. 118,435

Term of patent 7 years

(Cl. D14—3)

To all whom it may concern:

Be it known that I, Harvey W. Rockwell, a citizen of the United States, residing at Cedar Rapids, in the county of Linn and State of Iowa, have invented a new, original, and ornamental Design for Bulldozer, of which the following is a specification, reference being had to the accompanying drawings, forming a part thereof, in which

Figure 1 is a side perspective view of a bulldozer embodying my new design;

Fig. 2 is a front elevational view thereof;
Fig. 3 is a plan view thereof; and
Fig. 4 is a side elevational view of the main blade frame of the bulldozer.

The dotted line representation of the tractor in Figs. 1, 2 and 3 is for illustrative purposes only.

I claim:

The ornamental design for a bulldozer, substantially as shown and described.

HARVEY W. ROCKWELL.
